UNITED STATES PATENT OFFICE

97,109

DESIGN FOR A GLASS DISH

Everett Worthington and Findley Williams, Chicago, Ill., assignors to McGraw Electric Company, Chicago, Ill., a corporation of Delaware

Application July 27, 1935, Serial No. 57,828

Term of patent 3½ years

To all whom it may concern:

Be it known that we, Everett Worthington and Findley Williams, citizens of the United States, both residing at Chicago, in the county of Cook and State of Illinois, have invented a new, original, and ornamental Design for Glass Dishes, of which the following is a specification, reference being had to the accompanying drawing, forming part thereof, in which

Figure 1 is a top plan view of a glass dish showing our new design,

Fig. 2 is a view in end elevation thereof, and Fig. 3 is a transverse section therethrough, taken on the line 3—3 of Fig. 1.

We claim:

The ornamental design for a glass dish as shown.

EVERETT WORTHINGTON.
FINDLEY WILLIAMS.
